Specification of Letters Patent.

Patented Dec. 22, 1914.

Application filed July 5, 1912. Serial No. 707,815.

To all whom it may concern:

Be it known that we, FRANK N. REEVES and ALEEN E. LUNDELL, citizens of the United States, residing, respectively, at 5 Newark, in the county of Essex and State of New Jersey, and at New York, in the county of New York and State of New York, have invented a certain new and useful Improvement in Automatic Telephone-Exchanges, 10 of which the following is a full, clear, concise, and exact description.

This invention relates to automatic switching systems, and particularly to a telephone exchange system comprising one or more 15 main offices and one or more sub-offices or "satellites" associated and connected therewith by trunk lines. In a multi-office satellite system, there would be provided trunk lines leading from each main office to each 20 other main office of the system, and other trunk lines leading from each main office to its own satellites; and such a system may have, for example, ten main offices, each, with its satellites, having a capacity of 10,000 25 lines, making the capacity of the whole system 100,000 lines. The capacity of the satellites may be of, say, 500 subscribers' lines, each, although the number may vary according to requirements met in practice; and the 30 subscribers' lines may terminate either in a satellite or directly in a main office.

It is the object of this invention to economize in the use of trunk lines between the satellites and the main offices without requiring variable manipulation of the calling 35 devices to discriminate between calls local to a satellite and calls requiring connections through a main office. To this end automatic discriminating means is provided, 40 preferably at each satellite, operating without the necessity of any knowledge on the part of the party manipulating the calling device whether the subscriber called for is connected to the same satellite as the calling 45 subscriber or to a main office or some other satellite of the exchange. The calling device is manipulated in the same manner for all connections desired and strictly in accordance with the substation number of the 50 subscriber wanted.

The characteristic feature of this invention is, therefore, that it provides in an automatic satellite exchange system, means whereby a subscriber connected to a satellite

may be called without any discriminating 55 act at the calling device, wherever located in the exchange, to direct the connection, and without extending the connection through an inter-office trunk where the calling and called subscribers' lines terminate in the 60 same satellite.

There is preferably provided at each satellite in the system of this invention one or more register senders each adapted to be adjusted as by the impulses from the calling 65 devices which may be located at the subscribers' stations, and to control the automatic switches or selectors for establishing the desired connection. Each register sender 70 may comprise a plurality of switching devices or registers corresponding to the several orders of digits of the numbers of subscribers. Certain of these devices are provided with automatically adjustable contacts 75 so arranged and connected with other apparatus that if a subscriber is calling for another connected to the same satellite these contacts are concurrently operated whereby the connection is localized at the satellite, whereas if the call is for a subscriber connected to a main office or to another satellite, one or another of these contacts fails to be 80 operated whereby the connection will be automatically extended through a trunk line to a main office, and from there extended in 85 the usual way, under the control of the register sender to the desired subscriber's line.

The invention will be more readily understood by reference to the accompanying drawings wherein—

Figure 1 is a general plan or "lay-out" of a multi-office satellite telephone exchange system embodying the invention; and Figs. 2, 3, 4 and 5 when placed together from left to right in the order named represent the 95 circuits and apparatus involved in establishing connections between subscribers. Fig. 2 includes the apparatus associated with a calling subscriber of a satellite together with a portion of the register sender located at the satellite; Fig. 3 includes the remainder of the register sender; Fig. 4 represents a trunk selector at the satellite; and Fig. 5 represents a third and a final selector (or "connector") also at the satellite and a 100 called subscriber's line and station apparatus.

In Fig. 1 of the drawings, E represents a

main office connected by trunk lines 100 to other main offices A, B, C, D and F, it being understood that similar trunk lines would extend in such an exchange from each of such main offices to each other main office. 5 Associated with main office E are sub-offices or satellites E¹ and E². Similarly the other main offices may have satellites such as A¹, A², A³ for main office A¹, B¹, B², B³ for 10 main office B, etc. Subscribers' lines are connected some to the main offices directly, and others to the satellites; for example, two subscribers' stations e¹, e² are connected by lines 200 and 500 respectively to satellite E¹ and other subscribers' stations such as 15 e³, e⁴ are connected directly to the associated main office E. Similarly, main office D may have subscribers' stations d¹, d², d³, d⁴ the first two of which are connected to its 20 satellite D¹ and the last two directly to the main office D. The confines of the main office E are indicated by a dotted rectangle and may include a number of automatic 25 switches represented therein by a first selector 101, a second selector 102, a third selector 103 and a connector 104. The apparatus at a satellite such as satellite E¹ for example, may include such apparatus as a trunk finder 202 terminating the line 200, 30 a series of digit registers 203, 300, 301, 302 and 303, a trunk finder 402, a third selector 503, and connectors 504 and 105. The arrangement of apparatus thus diagrammatically shown in Fig. 1 and to be more fully 35 described with reference to the other figures of the drawings is such that the subscriber at station e¹ for example may obtain a connection to subscriber at station e² over a local trunk line such as 403, or he may obtain 40 a connection to any other subscriber of the exchange system whose line does not terminate at the satellite E¹ through a trunk line such as 406 leading to the main office E, from whence the connection may be extended 45 variously according to the particular location of the subscriber wanted. If any other subscriber than the one connected to the satellite E¹ desires connection with a subscriber connected to said satellite E¹, 50 the circuit would be completed by way of selectors such as 101, 102 and 103 at the main exchange E through a trunk line such as 106 to a connector such as 105 at the said satellite E¹. 55 It will hereinafter be stated in detail the manner in which a connection is directed from a subscriber at a satellite so that it will extend over a trunk line entirely local to the satellite, or will be extended through 60 an inter-office trunk line. At this point, it is sufficient to say that the trunk finder 402 is adapted to hunt for an idle trunk line in either of two series of trunk lines represented respectively by trunk lines 403 and 65 406, and its operative condition with respect

to these two series is determined by the automatically adjusted positions of the first three of the register sender switching devices 203, 300 and 301. And the adjusted positions of these devices are in turn determined and controlled by the first three movements of the substation calling device by which the subscriber indicates the tens of thousands, the thousands, and the hundreds digits of the number of the subscriber 75 wanted.

Referring to Figs. 2, 3, 4 and 5, wherein the circuits and apparatus required for the establishment of a connection between two subscribers—e¹, Fig. 2 and e², Fig. 5 are diagrammatically illustrated, each subscriber's line such as line 200, 201 of the calling subscriber e¹ is provided at the substation thereof with the usual telephone and signaling devices and a calling device or interrupter 204, and at the central office with a line relay 205 a cutoff relay 206 and a trunk finder 202. The line relay may have, as shown, two windings normally serially included in the subscriber's line together with the battery 207 through back contacts of the cutoff relay 206. The cutoff relay has two windings, one, a high resistance winding, 208, included serially with the front contact 209 in the circuit of a conductor 210 leading to feed ring 211 of the trunk finder, and the other, a low resistance locking winding, 212, adapted to be included with its own front contact 213 in the circuit of the same conductor 210, 213 being closed before the back contacts of 206 are opened. When energized the cutoff relay will disconnect the windings of the line relay and extend the circuit of line wires 200, 201 by way of conductors 214 and 215 respectively to other feed rings 216 and 217 of the trunk finder. 100

The trunk finder may comprise, as shown, a movable brush arm 218 carrying two sets of three brushes each, corresponding brushes of each set being connected together. One 110 set trails over feed rings while the other trails over sets of trunk contacts such as 219, 220, 221. A ratchet wheel 222 driven by a pawl 223 attached to the armature of a stepping magnet 224 comprises the power 115 mechanism for moving the brush arm. The type of trunk finder here shown is one which moves in one rotary direction only and when a half revolution of the brush arm has been made from the position indicated, the two 120 sets of brushes will exchange places, the upper one then resting on the feed rings and the lower one on the contacts.

The circuit of the stepping magnet 224 includes an intermittently operated vibrator 125 or interrupter 225, a battery 226, and a back contact 227 of cutoff relay 206; this circuit may be completed to ground either by way of a front contact 228 of the line relay 205, for starting the trunk finder 202, or by way 130

of a normally open contact 229 of the trunk finder for restoring it.

Branch conductors 230, 231 and 232 lead to terminals on connector switches, by which the subscriber at the station e^1 may be called. Conductors 230 and 231 are the line conductors and 232 is the test conductor. The latter is connected, when the trunk finder is in normal position, by way of contact 233 to the winding 212 of the cut-off relay 206, and, when the trunk finder is in off-normal position, by way of contact 234, to ground.

One of the trunk lines local to the satellite together with its associated register sender is shown in Figs. 2, 3 and 4 of the drawings. It is connected to the set of terminals 219, 220 and 221 of the trunk finder 202 and terminates in the trunk finder 400. The register sender comprises several switching devices or registers, 203, 300, 301, 302 and 303, one for each order of the digits of subscribers' numbers together with a similar switching device 240, the function of which is to control the resetting of the apparatus in case of premature disconnect on the part of the calling subscriber. There is also associated with the register sender a timing device 241 and a plurality of controlling relays, the functions of which will be stated presently. These various switching devices may be of any desired structure adaptable to perform the necessary switching operations, but as shown, each—for example, the "ten-thousands" register 203—comprises a shaft 242 carrying a plurality of cams controlling sets of contact springs; also a ratchet wheel 243 and driving pawl 244 attached to the armature of a stepping magnet 245 and an escapement 246 and controlling magnet 247 therefor. Rigidly mounted on the shaft 242 is a disk 262 carrying a retaining pawl 248 which engages a second ratchet wheel 249 which together with a star wheel 252 is secured to a sleeve 250 loosely mounted on said shaft. At the lower end of the shaft is a restoring spring 251, and in the normal position of the device a pin on the ratchet wheel 243 engages a stop 254. An interrupter or calling device 204 is adapted through circuits to be traced hereinafter to cause intermittent operation of the stepping magnet 245 to adjust the register to any position corresponding to the "ten-thousands" digit of subscribers' numbers. When thus moved away from normal a certain number of steps, the register is retained in such position by the escapement 246 until the latter is oscillated by intermittent energization of its controlling magnet 247 whereupon the register is restored to normal. During the advance movement, the pawl 248 passes freely over the teeth of the ratchet wheel 249 without moving it, but upon the return of the switching device under the control of the escape-

ment, the pawl engages a tooth of this ratchet wheel and carries the star wheel 252 with it. This results in a series of interruptions of a contact 253 corresponding in number to the number of steps the switching device had been advanced from its normal position by the stepping magnet 245. The several cams 235, 255, 256, 257, 258 and 263 are each (except 258) provided with a notch in which a contact spring rests when the register is in normal position, the positions of the switching elements being altered when the register is off normal. Cam 258 is so shaped that in its normal position it allows the contact spring, which it controls, to rest midway between opposing contacts 259, 261, but when off normal in all positions except number 6 it maintains the contact spring closed against the left contact 259. When in position 6, the numeral 6 being the "ten-thousands" digit of the group of subscriber lines served by this satellite, a raised portion 260 of the cam serves to lift the contact spring into engagement with the right contact 261.

The foregoing description of the register 203 applies to registers 300, 301, 302 and 303 except that certain of the cams and spring contacts are variously cut and arranged. For example, the cam 350 of the "thousands" register 300 is of the same general shape and performs the same function as cam 258 of the "ten-thousands" register, but the raised portion 305 by which the spring is lifted to close the right contact 360 is located in this case at position number 7 on the cam instead of position 6, 7 being the "thousands" digit of the group of lines of this satellite. In all other positions off normal the left contact 364 is closed. The corresponding cam 380 of "hundreds" register 301 is of somewhat different shape. During the first half revolution after leaving normal, including positions 0 to 4, the spring is lifted to close the right contact 370 whereas during the latter half of the revolution, including positions 5 to 9, it is allowed to retract and close the left contact 376.

The shapes of the cams 258, 350 and 380 are determined in the case of each satellite by the numerals representing the first two or three (varying according to the capacity of the satellite) digits of the particular group of subscribers' lines included in the satellite. Such a group may be, for example, lines 67,000 to 67,499. Thus the raised portion 260 of the cam 258, corresponds to the "ten-thousands" digit of these numbers; the raised portion 305 of the cam 350 likewise corresponds to the "thousands" digit, and the raised portion of the cam 380 corresponds to digits 0 to 4 inclusive comprising all of the hundreds digits of the numbers 67,000 to 67,499. It will thus be

130

seen that the three cams 258, 350 and 380 will lift their springs to close the right contacts 261, 360 and 370 simultaneously only when the ten-thousands, thousands and hundreds registers are advanced seven steps, eight steps and from 1 to 5 steps respectively from normal. Such a condition, as will be more freely explained hereinafter, results in the establishment of a circuit by which the 5 trunk finder 400 will be started in search of an idle trunk line local to the satellite. If, however, any other combination of positions is obtained, such circuit will not be closed and the trunk finder 400 will be 10 caused to hunt instead for a trunk line extending to the main exchange. It will be understood that for all other cams of the registers than those mentioned, namely, 258, 350 and 380, the sets of spring contacts 15 controlled thereby, are capable of assuming but two positions, one the normal as indicated, and the other the off normal. Certain of these such as those operated by cams 256 and 257 of the "tens-thousands" register 20 25, are of the make before break type while others such as those operated by cam 263 are of the break before make type. Still others such as that of the cam 255 have but a single contact closed when the register is off normal. Single contact of cam 285 is closed at 30 normal.

The resetting device 240 and the timing device 241 are each adapted to move in but one rotary direction and when moved away 35 from normal to make a complete cycle and return to normal. The several cams 267, 268, 269, 271, 272 and 273 of the resetting device 240, with the exception of cam 269, control sets of spring contacts in a manner 40 similar to that of the registers. Cam 269 however, is arranged to close its contact 274 at each of several alternate steps, viz., 1, 3, 5, and 7 steps away from normal. The timing device 241 has a single cam 275 controlling a single contact 276 which is closed when this device is off normal.

When the circuit of the calling subscriber 50 is extended by the operation of the trunk finder 202 to the trunk line terminating in contacts 219, 220 and 221, the cut-off relay 206 will have been operated, opening the circuit of line relay 205, and the subscriber's line circuit will have been extended by way of conductors 277 and 278, and current will 55 be supplied from battery 279 over the coils of the register line relay 281. The cut-off relay 206 is during such time maintained energized over a circuit completed by way of the third or local conductor 282 of the trunk line. The register line relay 281 is energized by current flowing in the line and is, therefore, responsive to the line interruptions which follow upon the movements of the subscriber's calling device 204. This relay 60 controls the circuits of slow release re-

lays 283 and 284. Other relays 285 and 286 which are quick acting are also controlled by the register line relay and in turn control the advance movement of the "ten-thousands" register 203 of the register 70 sender. The "ten-thousands" register also has associated with it relays 287 and 288 which cooperate with the timing device 241 for sending impulses to the selectors and with the resetting device 240 for controlling 75 restoration upon a premature disconnect by the calling subscriber.

In Fig. 3, relays 306 and 307 for the "thousands" register, relays 308 and 309 for the "hundreds" register, and relays 311 and 312 for the "tens" register correspond in function with the relays 287 and 288 (Fig. 2) for the "ten-thousands" register. Similarly, relays 313 and 314 for the "thousands" register, 315 and 316 for the "hundreds" register, and 317 and 318 for the "tens" register correspond in function to relays 285 and 286 of the "ten-thousands" register. This will more fully appear hereinafter in the detail description of the operation of the system.

Associated with the interrupter 304 is a pair of relays 319 and 321, the function of which, as will more fully appear hereinafter, is to insure the closure of the impulse 95 circuit for the escapement magnet 247 of the register 203 in such a manner that the first impulse always will be a full one.

It will be understood that in completing a connection local to the satellite, the "ten-thousands" and the "thousands" sets of impulses will not be required, the first set needed in such a case being the "hundreds" set of impulses. Accordingly, a relay 822 is provided having two normally open contacts 323 and 324. This relay will be energized on a local call, and by its contact 323 will shunt contacts 253 and 343 and thus prevent the sending of the "ten-thousands" and the "thousands" sets of impulses. Contact 324 of relay 322 is adapted to close a battery circuit by way of contact 325 of the units register for starting the sending impulses upon a local call.

The trunk finder 400 is of the same general construction as trunk finder 200. It is provided, however, with four sets of feed rings 409, 411, 412 and 413, and two sets of four brushes. These sets of brushes are mounted on opposite ends of a brush arm 414 and are respectively cross connected and are adapted to trail over the feed rings and sets of trunk contacts such as 415, 416, 417 and 418. Contacts 415, 416 and 418 are connected to local trunk line conductors, 403, 115 404, 405, while another set, in which 417 is used instead of 418, is connected to trunk line conductors 406, 407, 408, leading over trunks to the main office. Preferably the connections with such trunk lines alternate, that 120 125 130

is to say, sets Nos. I, III, V and VII are for local trunks, and sets Nos. II, IV, VI and VIII are for outgoing trunks. The third or test conductors of the local trunks are connected 5 to the inner row of terminals 418, whereas such conductors for the outgoing trunks are connected to the next to the inner row of terminals 417. A stepping magnet 419, directly under the control of the interrupter 10 421, is adapted to advance the trunk finder over the terminals step-by-step when the proper circuits are established for causing it to hunt for an idle trunk in either series. For the purposes of controlling the trunk 15 finder in advancing and returning, there are provided several contacts, 422 which is normally open, and 423 and 424 which are normally closed. There are also provided two test relays 425 and 426, and a starting 20 relay 427. Relay 425 or relay 426 becomes operative according as to whether the trunk finder is hunting for an outgoing trunk or a local trunk. Associated with the local test conductor 408 of the outgoing trunk is a 25 resistance 428, battery 429, and the relay 431, the purpose of which will more fully appear hereinafter.

As hereinbefore stated, calls local to a satellite will be extended beyond the trunk 30 finder 400 through and by means of a third selector 503 and a connector 504. Such apparatus is well known and need not be fully described here. The selector may be of the two-movement type wherein a series of steps 35 are taken to select the desired group of connectors and then automatically hunt for an idle connector in the group. Likewise, the connector may be of the two-movement type in which the line wanted is selected by two 40 series of steps. There is shown in Fig. 5 the talking circuit conductor of such apparatus including the main switch contacts 505 and 506 of the selector 503, and 507 and 508 of the connector 504; also condensers 45 509 and 511, and impedance coil relays 512 and 513 connected in bridge of the talking circuit on either side of the condensers, and supplying current through their respective windings from battery 514 to the calling and 50 called subscribers' lines. Associated with the local test conductor 405 of the local 55 trunk, shown in Fig. 4, are the resistance 515 and release magnet 516 corresponding in some of their functions with the resistance 428 and relay 431, as will more fully appear hereinafter. Associated with the selector and connector switches 503 and 504 there would preferably be local test and holding contacts 517 and 518 respectively. 60 The brush of the latter is adapted to be connected to ground 519 when the connector is operated, the object of this being to create a busy test condition for other connector switches and for operating the 65 cutoff relay 206 of the called line. It will

be understood that the line of each called subscriber will have associated with it a trunk finder and line and cutoff relays, such as shown in association with the line of the calling subscriber e^1 , and that the connections for such apparatus will be made by the conductors 521, 522 and 523 corresponding to conductors 230, 231 and 232 of the calling subscriber's line.

The operation of the system will now be 75 described. Let it be assumed that the subscriber at station e^1 is calling for the subscriber at station e^2 , these two stations being connected to the same satellite; and let it be further assumed that this satellite includes 80 a group of 500 subscribers' lines numbered from 67,000 to 67,499, and that the number of the called subscriber's line is 67,321. The calling subscriber at station e^1 removes his telephone thereby closing the line circuit 85 through line relay 205, the current flowing over the following path:—207, 205, back contact of 206, 200, apparatus at station e^1 , 204, 201, back contact of 206, 205, ground. Line relay 205 closes at contact 228 the circuit of the stepping magnet 224 including the interrupter 225 over the following 90 path:—226, 225, 224, 227, 228, ground. The intermittent operation of the interrupter 225 causes the trunk finder 202 to take one 95 or more steps away from normal in search of an idle trunk line, and it is assumed here that two steps are taken, the first trunk line being busy. The busy condition of test terminals is caused by the altered potential due 100 to current flowing from battery through the low resistance winding 212 of a test or cutoff relay 206 associated with some other line. In such case the high resistance winding 208 of the relay testing would be shunted by 105 that low resistance winding and the former would receive insufficient current for its energization. As the trunk finder leaves normal, contact 229 is closed in parallel with contact 228, thus insuring the continued 110 operation of the trunk finder without regard to the continued energization of the line relay. At the same time a ground is placed on conductor 232 at contact 234 thus leaving a busy test condition at the terminals of the 115 calling line located on connector switches, and also contact 233 is opened taking away the control of the cutoff relay from other connecting switches which may be seeking this line. The closure of contact 209 by 120 the line relay places the winding 208 of the cutoff relay 206 in condition to receive current when the trunk finder 202 finds an idle trunk, and under the assumption that the trunk line shown in the drawing is the first 125 idle one this current will flow over the following path:—207, 209, 208, 210, 211, the inner brushes of 202, 221, 282, contact 397 of release relay 396, 289, 290, relay 291, ground. The cutoff relay is energized dis- 130

connecting the line relay and extending the circuit of the calling subscriber's line through the trunk finder to the register line relay 281 and battery 279, current now flowing in the subscriber's line over the following path:—279, 281, 292, 424, 293, 277, 219, 216, 214, front contact of 206, 200, the apparatus at substation e^1 , 204, 201, front contact of 206, 215, 217, 220, 278, 294, 423, 295, 281, ground. This current causes the energization of the register line relay 281 which closes at its front contact a local circuit of slow release relay 283, independent of that closed by relay 291. Relay 283 closes at its contact 296 a path leading to the second slow release relay 284, the circuit of the latter, however, being open at this moment at the back contact 297 of relay 281. Relay 283 also opens a ground connection at contact 298 which maintains, during the sending operation, the circuit of the stepping magnet 299 of the reset device 240 opened; it also closes a ground connection at contact 11 for the flow of current subsequently through relays 285 and 288.

The apparatus is now in condition for the sending of impulses over the subscriber's line to register the number of the line wanted, which according to the assumption is number 67,321. The calling device or impulse transmitter indicated as 204 at the calling substation e^1 may be of any suitable construction for producing successively several series of line interruptions indicated by the digits of the number of a subscriber wanted. There will thus first be produced by this calling device a series of seven impulses, one additional impulse being sent because the first numeral is, in the system described, 0 instead of 1. Each interruption causes the deenergization of register line relay 281, and therefore, a momentary release of its armature and closure of contact 297. Slow release relay 283 remains energized notwithstanding the momentary interruptions of its circuit at the front contact of the line relay 281 and, therefore, contact 296 remains closed, and each time contact 297 is closed current flows through the slow release relay 284 and the stepping magnet 245 of the "ten-thousands" register, the circuit being as follows: 12, 245, 10, 284, 296, 297, ground. This results in the stepping forward of the "ten-thousands" register 203 seven steps and, therefore, in the closure of contact 261. The first impulse of current in slow release relay 284 results in its energization, and this relay remains energized continuously so long as the current impulses continue in its local circuit, that is to say, while the first series of line interruptions take place. Upon its energization relay 284 closes a local circuit of relay 286 by

way of its front contact 13, back contact 14 of relay 285 and battery 15; and the energization of 286 in turn closes a locking circuit for itself by way of its front contact 16. Relay 285 is not energized, however, because short-circuited by the path to ground through contacts 13 and 14. When, however, the seven interruptions have taken place the line circuit again becomes steadily closed and contact 297 remains open so that relay 284 releases its armature, opening contact 13, whereupon relay 285 becomes energized to prepare the apparatus for delivering the next series of impulses to the "thousands" register 300. The circuit for relay 285 is over the following path:—15, 286, 16, 285, 11, ground, and these relays will remain energized over this path under the control of relay 283 until the register line relay 281 shall become disconnected from the circuit.

The next series of line interruptions, eight in number corresponding to the second digit 7 of the called subscriber's number, the additional interruption being for numeral 0 as before, results in a stepping forward of the "thousands" register 300 eight steps, at the end of which relay 313 becomes energized in the same way that relay 285 was previously, whereupon the local circuits controlled by the register line relay 281 are shifted to the relays 315 and 316 of the "hundreds" register 301. Four interruptions now follow resulting in four impulses to the stepping magnet of this register, whereupon relay 315 is energized as relays 313 and 285 were previously. Following this, three interruptions occur resulting in the advance of the "tens" register three steps, whereupon relay 317 is energized, and finally two impulses are received by the stepping magnet of the units register 303, resulting in its advance to position 1. The several registers, comprising the register sender, are now set away from normal seven, eight, four, three and two steps, respectively, thus indicating and registering the number 67,321 of the subscriber wanted. When the last impulse is received by the "tens" register, the current in the subscriber's line becomes steady again and slow release relay 284 opens its contact 13 thus permitting the energization of relay 317 which had been, during the sending of the "tens" impulses, short-circuited in the same manner that relay 285 had been during the sending of the "ten-thousands" impulses. The circuit for relay 317 is then as follows:—334, 318, 335, 317, 18, 11, ground. The circuit for the last series of impulses for advancing the units register is as follows:—326, 327, 328, stepping magnet 329, 331, 332, 333, 17, 284, 296, 297, ground.

This circuit includes contact 327 of the "tens" register which is open when the "tens" register is in normal position. The trunk finder 400 is started in its search for an idle trunk line either outgoing or local as soon as the "tens" register moves one step away from normal, the circuit being made operative for this purpose by the closure of contact 336. This completes the ground connection through conductor 18 and contact 11 of relay 283 for the starting relay 427, the circuit being as follows:—battery 430, 427, 19, 336, 18, 11, ground. Previously, by reason of the particular set conditions of the "ten-thousands", "thousands" and "hundreds" registers, the call being assumed to be one between subscribers of the same satellite, a circuit had been prepared for the local test relay 426 by way of contacts 261, 360 and 370, and the closure of contact 336 provided the ground path by way of conductor 18 for this test circuit which is to be completed, when the brushes of the trunk finder 400 rest upon the terminals of an idle local trunk line as will be explained presently. The trunk finder is stepped ahead by the intermittent operation of stepping magnet 419, the circuit being as follows:—battery 430, 431, 432, 433, 434, 419, 421, ground. This circuit leads through the back contacts 433 and 434 of test relays 425 and 426, and therefore the continued operation of the trunk finder depends upon the continuity of these contacts. The circuit of the outgoing test relay 425 is open at this time at the contacts 259 of the "ten-thousands" register, 364 of the "thousands" register, and 376 of the "hundreds" register, so that the busy or idle condition of the outgoing trunk lines will have no effect upon this relay. As soon, however, as an idle local trunk is found, say the trunk line connected to terminals 415, 416 and 418, a circuit will be established for the local test relay 426 as follows:—battery 524, 515, 525, 405, 418, inner brushes of trunk finder 414, 413, 435, 341, 370, 360, 261, 19, 336, 18, 11, ground. The energization of the test relay 426 causes the closure of a shunt path for its winding 435 by way of a low resistance locking winding 436 and contact 437. The increased flow of current due to the shunting effect of winding 436 causes a change in potential at the test terminal 418 of the trunk line whereby other trunk finders in testing for idle trunk lines will find this one busy. It will be understood that these terminals are connected in multiple with corresponding terminals on other trunk finders. At the same time contact 434 being opened stops the operation of the stepping magnet 419, and therefore the trunk finder stops with its brushes in contact with the trunk line terminals 415, 416, 418. Relay 426 when energized also closes contacts 438

and 439 in the talking circuit leading to feed 65 rings 409 and 411 respectively, and contact 441 which closes a circuit for relay 322 as follows:—battery 430, 431, 432, 433, 441, 342, 322, 18, 11, ground. The energization of relay 322 causes the short-circuiting at contact 323 of the interrupter contacts 253 and 343 of the "ten-thousands" and "thousands" register respectively, and also closes at contact 324 a circuit for relay 321 which is preliminary to the sending of impulses for the 75 return of the several registers, this circuit being as follows:—430, 431, 432, 345, 324, 346, 325, 347, 321, 348, 349, 304, ground. This circuit includes the interrupter 304 which may or may not at that instant have its contact closed. The closure, however, will be almost immediate and result in the energization of relay 321 which, by the closure of its contact 351, will prepare relay 319 for operation as soon as interrupter 304 opens 85 its contact. The circuit previously traced for relay 321 will thereupon continue from its winding through 319, 18 and 11 to ground, instead of directly to ground through 348, 349 and 304. Relay 319 is thus 90 energized whereupon a stepping circuit for the escapement magnet 247 of the "ten-thousands" register is established by way of the front contact 352 as follows:—battery 22, 247, 23, 38, 24, 25, 352, 304, ground. A 95 succession of impulses for the escapement magnet 247 follows. These are equal in number to the number of steps—seven under the present assumption—corresponding to the number of advance steps made by this 100 register under the control of the stepping magnet 245. The "ten-thousands" register returns to normal whereupon contact 23 is opened and contact 26 is closed, a circuit being thereupon established for the operation 105 of the timing device 241 as follows:—battery 27, stepping magnet 31, 32, 28, 26, 38, 24, 25, 352, 304, ground. As soon as the timing device leaves normal it closes contact 276 thereby energizing relay 287 in the following circuit:—33, 287, 34, 37, 276, ground. And relay 287 in energizing closes contact 35 which controls relay 288, now short-circuited in the circuit just traced, for subsequent energization when the timing device 115 returns to normal, and thus opens the short-circuit at contact 276. Relay 288 thereupon becomes energized and opens at contact 24 the circuit for the stepping magnet 31 of the timing device, and at the same time opens 120 contact 34 and maintains itself and relay 287 energized in the following circuit:—battery 33, 287, 35, 288, 36, 11, ground. Relay 288 also extends the circuits of conductors 37 and 25 by way of front contacts 39 and 41 to conductors 42 and 43, respectively. The function of the timing device 241 is to 125 delay the operation of the "thousands" reg-

ister following that of the "ten-thousands" register for a sufficient length of time to permit trunk hunting.

- During the return of the "ten-thousands" register contact 253 will be broken seven times. This in the case of an outgoing call would result in a succession of seven interruptions in the circuit extending to a first selector, but in the case under consideration 10 where the call is between subscribers in the same satellite, these interruptions will have no effect in the circuit because contact 253 is short-circuited by contact 323 of relay 322.
- 15 The "thousands" register is now operated in the same manner as the "ten-thousands" register had been, the timing device operating after its return to normal, and relays 306 and 307 operating one after the 20 other in the same manner as relay 287 and 288 of the "ten-thousands" register. The succession of interruptions at contact 343 has no effect in the operation of a selector because as previously explained it and contact 253 of the ten-thousands register are 25 now short-circuited by contact 323 of relay 322. Upon the energization of relay 307 the stepping circuit for escapement magnet 353 is closed over the following path:—battery 354, 353, 355, 356, 357, 43, 41, 25, 352, 304, ground. The "hundreds" register is given four impulses and returns to normal, whereupon its escapement magnet 353 is disconnected from the circuit at contact 355, 30 35 and the timing device 240 is brought into operation with the interrupter 304 over the following circuit:—battery 27, 31, 32, 28, 358, 356, 357, 43, 41, 25, 352, 304, ground. And while it is off normal a circuit is 40 established for relay 308 over the following circuit:—battery 359, 308, 361, 362, 42, 39, 37, 276, ground. Relay 308 on being energized closes contact 363 controlling relay 309 for subsequent energization—it now being short-circuited—when the timing device 241 returns to normal and opens contact 276. When energized relay 309 extends the control circuit for the operation of the "tens" 45 register which received three impulses causing three interruptions of contact 365, whereupon it is returned to normal and starts the timing device 241 much in the manner before stated. 241 makes one cycle, and then causes the energization of relay 50 312 which brings the units register into operation, its escapement magnet 366 receiving two impulses in the circuit of the interrupter 304. This circuit is as follows:—battery 367, 366, 395, 368, 369, 357, 43, 41, 25, 352, 304, ground. The units register 55 60 65 303 in returning to normal opens its contact 371 twice. Thus the "hundreds," "tens" and "units" registers in returning to normal deliver four, three and two impulses, respectively, in the circuit of the

trunk line 403, 404, which at this time is in circuit with the trunk line 372, 373, through the trunk finder 400. It will be noted that as soon as the "tens" register left its normal position in being set a short circuit of the trunk line conductors 372, 373 was established through contacts 374, 323, 375, 365 and 371; also that upon the operation of each of the registers in turn the main trunk line conductors 277 and 278 were interrupted as, for example, at contacts 44, 45, and closed through contacts 46 and 47 directly to the register line relay 281. This shifting of the main trunk line conductors serves to open the circuit forward to the 80 selectors while maintaining it closed back to the calling subscriber, and the paths to the register line relay take the place of the normal paths through contacts 423 and 424 of the trunk finder 400. The short-circuit 85 of the trunk line conductors 372, 373, is maintained at contact 399 of the "units" register after being opened at contact 374 of the "tens" register when the latter has returned to normal.

Only so much of a third selector and final selector or connector are shown in Fig. 5 as is necessary to illustrate the principal signaling and talking circuits to a called subscriber's station e^1 . When the trunk finder 95 makes the connection with the trunk line conductors 403, 404, 405, and when the "tens" register has left normal, a circuit is established, preparatory to the sending of the "hundreds" impulses, as follows:—battery 526, relay 527, 403, 415, the outer brushes of the trunk finder 400, 409, 438, 372, 372, 374, 323, 375, 365, 371, 373, 439, 411, the next to the outermost set of brushes of the trunk finder 400, 416, 404, 527, to 100 ground. This causes the energization of relay 527 and prepares the third selector 503 for operation in a well-known manner by the impulses which subsequently occur upon the return of the "hundreds" register 301 to 110 normal. After the passage of these impulses and the following automatic selection of a trunk line to an idle final selector or connector during the time of the operation of the timing device 241, the next, or "tens", 115 series of impulses follow over the same circuit extended, however, to battery 514 and relay 512 of the connector. Finally the last series of impulses occur when the "units" register returns to normal whereupon the 120 connector is given a second movement to the terminals of the line wanted. Any well-known method may be employed for signaling the called subscriber, and upon his response by lifting his telephone from its 125 switch hook a complete talking circuit is established. This circuit is shown in heavy lines in the drawings and can be traced from the switchhook of the calling subscriber e^1 130 as follows:—200, 214, 216, outer brushes of

trunk finder 202, 219, 277, 44, 377, 378, 379, 381, 372, 438, 409, outer brushes of trunk finder 400, 415, 403, 505, 509, 507, 501, apparatus at substation e^2 , 500, 508, 511, 506, 404, 516, next to the outer brushes of trunk finder 400, 411, 439, 373, 382, 383, 384, 385, 45, 278, 220, middle brushes of trunk finder 202, 217, 215, 201, calling device 204, and apparatus at substation e^1 . Current is supplied in this circuit from battery 514 by way of the windings of relay 512 to the calling line, and relay 513 to the called line, the talking circuit being interrupted to battery current between the connections of these relays by condensers 509 and 511.

Under the foregoing assumption that the subscriber calling and the subscriber called for were connected to the same satellite, it was pointed out that the local test relay 426 was made operative due to the particular setting of the "ten-thousands", "thousands" and "hundreds" register and to the simultaneous closure of contacts 261, 360 and 370 in the circuit of that relay. In case, however, the subscriber called for is connected directly to a main office or to some other satellite than the one to which the calling subscriber is connected, the circuit to the local test relay 426 will not be closed due to the failure of one or the other of said contacts 261, 360 and 370 of the "ten-thousands", "thousands" and "hundreds" registers being closed; and in such case the outgoing test relay 425 will be placed in operative condition instead, its circuit becoming closed at one or the other of the following alternative contacts 259, 364 and 376. Thus, if the call is for number 67,555, contacts 261 and 360 of the "ten-thousands" and "thousands" register will be closed, but contact 370 of the "hundreds" register will be opened, and instead contact 376 will be closed, the circuit of test relay 425 being over the following path:—battery 429, 428, 451, 408, 417, the next to the inner set of brushes of trunk finder 400, 412, 453, 389, 376, 360, 341, 261, 19, 336, 18, 11, ground, thus causing the outgoing test relay 425 to operate and close its low resistance winding 454 in shunt of its high resistance winding 453 by way of the locking contact 455. This relay in operating also opens contact 433 which stops the operation of the stepping magnet 419 of the trunk finder 400; and closes contact 465 thereby completing the following circuit for the operation of relay 321, which as before explained, is preliminary to the commencement of the impulses for returning the registers to normal:—battery 430, 431, 432, 465, 391, 325, 347, 321, 348, 349, 304, ground. In this case the relay 322 is not operated, and the impulse-sending contacts 253 and 343 are therefore not short-circuited so that the sending of the "ten-thousands" and "thou-

sands" impulses will result in the operation of first and second selector mechanisms, as well as the third and final, suitably arranged at the main or other offices to which the circuit is now extended. In either case, that is whether the circuit is extended to a third selector, such as 503 at the satellite, or to a first selector, such as 101, at a main office, the circuit formerly established through the register line relay 281 to the calling line will be broken at contacts 392, 393, when the "units" register returns to normal, and a through circuit established as before traced by way of contacts 381 and 382, current being supplied over this circuit to the calling line from a battery and the windings of a selector line relay at the switch to which the circuit is extended. It will be noted that this relay, such as relay 527 of the third selector 503, will first receive current through the short circuit of line conductors 372, 373 over the following path:—372, 374 and 399 in parallel, 253, 343, 375, 365, 371, 373. This will give ample time for the apparatus at the selector to get into condition for receiving the impulses which follow.

When the subscribers hang up their telephones to disconnect the apparatus of the selectors beyond, (or to the right in the diagram) the trunk finder 400 may be restored according to any known method, it being assumed that the release magnet 516 will be energized upon the restoration of the third selector 503, whereupon the circuit previously traced for the local test relay 426 will be opened at contact 525 whereupon said relay 426 will be deenergized causing the closure of the following circuit:—battery 456, contact 422, 432, 433, 434, 419, 421, to ground. Stepping magnet 419 in this circuit will advance the trunk finder 400 around in the same direction it was originally moved to a normal position. This will be one-half revolution of the brush arm 414 from the position at which it started. A branch of the circuit just traced includes the release relay 396, the circuit being as follows:—battery 456, 422, 432, 433, 434, 457, 398, 396, ground. This relay thereupon opens its contact 397 in the circuit of the test conductor 282, thereby opening the circuit of the cutoff relay 206 which in turn closes contact 227 in the circuit of the stepping magnet 224, which circuit is as follows:—battery 226, 225, 224, 227, 229, ground. The trunk finder 202 is thus restored to normal in the same manner as the trunk finder 400. All apparatus involved in the connection is now restored to normal, and is ready for service on subsequent calls.

In the case of a connection over an outgoing trunk line the relay 431 would be energized in a manner similar to the energization of relay 516, whereupon the circuit of outgoing test relay 425 would be opened at

contact 451 and the apparatus restored to normal as in the case of a local connection. Should the calling subscriber at ^{e1} hang up his receiver prematurely, that is after having started to send a call, but before receiving a connection, any one or more of the registers 203, 300, 301, 302 or 303 that may be off normal will be returned to normal by means of the resetting switching device 240 actuated by stepping magnet 299, its circuit being closed at contact 298 by the armature of slow release relay 283 when the circuit of register line relay 281 is held open by the receiver hook. Take, for example, a case where the calling subscriber at ^{e1} hangs up immediately after setting all the registers, but before the "ten-thousands" register 203 has been returned to normal. The circuit of stepping magnet 299 will be closed at 298 and current will flow over the following path:—battery 280, 299, 73, 48, 298, ground. Switching device 240 is moved from normal to position 1. As soon, however, as 240 leaves normal, its cam 273 opens at contact 73 the circuit just traced, but cam 271 at the same time closes contact 71, thus preparing a new circuit for 299. Cam 272 opens at contact 290 the circuit of cut-off relay 206 whereupon contact 227 is closed and trunk finder 202 returns to normal. Cam 268 closes contact 68 thus energizing relay 321 over the following path:—battery 69, 68, 270, 347, 321, 348, 349, 304, ground.

As is the case when register 203 is returned to normal, as described in connection with a completed call, the closure of relay 321 will prepare relay 319 for operation as soon as interrupter 304 opens its contact. Relay 319 upon being energized closes a stepping circuit for escapement magnet 247 of the "ten-thousands" register 203 over the following path:—battery 22, 247, 23, 38, 24, 25, 352, 304, ground. A number of impulses sufficient to return 203 to normal will be sent by means of interrupter 304. Upon 203 reaching normal, contact 23 is opened and 26 closed. But since 240 is in position 1 instead of normal, and contact 32 is opened, timing device 241 will not be operated as described in connection with a normal return of 203. Instead, since contact 71 is closed, a circuit for stepping magnet 299 to move 240 from position 1 to 2 will be closed over the following path:—battery 280, 299, 71, 28, 26, 38, 24, 25, 352, 304, ground.

In position 1 of 240, as when the timing device 241 is actuated in the normal operation of resetting the "ten-thousands" register 203, the relay 287 is energized but its circuit to ground is through contact 274 of 240 instead of 276 of 241. A circuit is also prepared for relay 288, but as when 241 is operated it is short circuited until 275 re-

turns to normal, it is likewise short circuited

in position 1 of 240. When 240 reaches position 2, however, this short circuit is broken at 274 and relay 288 is energized opening at contact 24 the circuit for 299 which caused it to move 240 from position 1 to position 2, and at the same time opening contact 34 and maintaining itself and relay 287 energized in the following circuit:—battery 33, 287, 35, 288, 36, 67, ground. Relay 288 also extends the circuit of conductors 37 and 25 by way of front contacts 39 and 41 to conductors 42 and 43.

In position 2 of 240 the "thousands" register 300 is returned to normal the same as was the "ten-thousands" register 203, 80

the circuit of escapement magnet 320 being as follows: Battery 310, 320, 330, 338, 43, 41, 25, 352, 304, ground. When 300 reaches normal, contact 330 is opened and contact 337 is closed.

Stepping magnet 299 then is 85 energized over the following path: Battery 280, 299, 71, 28, 337, 338, 43, 41, 25, 352, 304, ground. 240 thereupon is moved from position 2 to 3 and relay 306 is energized as was relay 287, but the circuit 306 prepares 90 for 307 is short circuited by the closure of contact 274 as was the circuit 287 prepared for 288.

Since, however, the circuit of 299 is not opened in position 3, 240 continues into position 4 where the short circuit is 95

broken at 274 and relay 307 is energized over the following path: Battery 339, 306, 344, 307, 18, 36, 67, ground. This opens the circuit of 299 at contact 338 and 240 comes to rest in position 4. Conductors 42 and 43 100

are extended at contacts 362 and 357. At the latter contact the circuit of escapement magnet 353 of the "hundreds" register 301 is closed over a circuit very much the same as was 320 of "thousands" register 300, the 105

path being as follows: battery 354, 358, 355, 356, 357, 45, 41, 25, 352, 304, ground. In the fourth position, therefore, the "hundreds" register 301 is returned to normal. When it arrives at normal, it opens at its contact 110

355 the circuit of its escapement magnet 353 and closes instead at its contact 358, the circuit of stepping magnet 299 of switching device 240, whereupon the latter is moved from position 4 through position 5 into position 6 where relay 309 is energized, as were 115

relays 288 and 307, opening at its contact 356 the circuit of 299. In position 6 of 240 the "tens" register 302 is returned to normal since the circuit of its escapement mag-

net 390 is closed by relay 309 at contact 369. Arriving at normal 302 opens at its contact 120

387 the circuit of 390 and closes instead that of 299 whereupon 240 is moved from position 6 through 7 into 8 where relay 312 is 125

energized opening the circuit of 299 but closing at its contact 368 the circuit of es- 130

capement magnet 366 of the "units" register 303 over the following path: battery 367, 368, 395, 368, 369, 357, 43, 41, 25, 362, 304,

363, 395, 368, 369, 357, 43, 41, 25, 362, 304, 135

ground. "Units" register 303 then is returned to normal opening at its contact 395 the circuit of 366 and closing instead at its contact 394 the circuit of stepping magnet 299 which then continues to step along the switching device 240 until it arrives at normal and opens its contact 71, 68 and 67. The circuit of stepping magnet 299 is opened at 71, battery is removed from relays 321 and 319 at 68, while at 67 the circuit to ground of the locked up relays 287, 288, 306, 362, 308, 309, 311, 312, is opened, after which all the apparatus is again in normal position and the trunks ready to be taken for another call. Until 240 returns to normal and closes contact 290 there will be no ground on the test conductor of this trunk, and therefore it will give a busy test during all the time the apparatus is being returned to normal. From position 8 to normal, cam 269 of switching device 240 is regular, that is, it has no further depression such as it has in positions 2, 3, 5 and 7, so that its contact 274 might complete circuits to ground in these positions for relays 287, 306, 308 and 311 respectively. After 311, no further relays of this type, used as above described in shifting the circuit through interrupter 304 from stepping magnet 299 to the several register release magnets, are needed.

In the case of a premature disconnect that occurs after the tens register 302 has been moved off normal, such as the one above described, or one where 302 but not 303 has been moved off normal, the trunk finder 400 will be moved off normal and will connect with an idle trunk, since its release relay 427 is energized as soon as contact 336 of 302 is closed. Further, this connection, as in a normal call, will be extended to a connector such as 504 upon the return to normal of the registers 203, 300, 301, 302 and 303 under the influence of switching device 240. Therefore, even if impulses are not sent from the units register 303, the relay 512 will be included in the talking circuit. In the normal sending of a call, the circuit of relay 512, upon the return to normal of units register 303, before being broken at its contact 399, would be closed at its contacts 381 and 382 and extend over the talking circuit to the calling subscriber at e^1 . But in the case of a premature disconnect, such as referred to above, since the receiver is on the hook and the circuit through e^1 broken, the circuit of relay 512 will be broken at 374 upon the return to normal of 302, or, if the units register 302 had been set, upon its return to normal and at its contact 399. When relay 512 is deenergized, it opens at its contact 540 the circuit of slow-release relay 542, which in turn opens at its contact 543 the circuit of slow-release relay 533. Therefore, since 503 is off normal and its contact

530 closed, release magnet 516 will be energized upon the closing of contact 534 of slow-release relay 533, current flowing as follows: battery 524, 516, 530, 534, 532, ground. Release magnet 516 thereupon opens at its contact 525 the circuit of test relay 425, or if 431 had been energized instead of 516, the circuit of outgoing test relay 426 would have been opened at 451. In either case, the circuit of stepping magnet 419 is closed as in a normal call over the following path: battery 456, 422, 432, 433, 434, 419, 421, ground, and the trunk finder 400 returned to normal where the circuit just traced is broken at contact 422. If, for example, the calling subscriber at e^1 hangs up his receiver after having set the "ten-thousands" register 203 and the "thousands" register 300, they will be returned to normal as previously described. After attending to the return of 203 and 300 the switching device will also be returned to normal. In this connection it will be remembered that when the "thousands" register 300 returns to normal it closes at its contact 337 the circuit of stepping magnet 299 which thereupon moves the switching device 240 from position 2 to 3 where relay 306 is energized, then to position 4 where relay 307 is energized. The latter closes at its contact 357 the circuit of stepping magnet 299 over the following path, since the "hundreds" register 301 is at normal and its contact 358 closed: battery 280, 299, 71, 28, 358, 356, 357, 43, 41, 25, 352, 304, ground. The switching device 240 thereupon will be stepped around from position 4 to 6, relay 308 being energized in position 5 and relay 309 in position 6. The circuit of 299 is contained at 369 since the "tens" register 302 is also at normal and its contact 386 closed. 240, therefore, continues to move under the influence of 299, relay 311 being energized in position 7 and relay 312 in position 8. Since contact 394 of the "units" register 303 is also closed, 299 will continue to advance 240 until it arrives at normal and opens at its contact 71 the circuit of 299. All the apparatus is now at normal and the trunk ready for use in another call.

If the calling subscriber at e^1 should hang up the receiver after the call has progressed to the point where several registers have returned to normal while others are still off normal, the latter will be returned as already described. Take, for example, the case where the registers 203, 300 and 301 have been returned to normal while registers 302 and 303 have not yet sent their impulses to the final connector and are therefore still off normal. The stepping magnet 299 of the switching device 240 is actuated over the circuit to ground closed as before at 298, and in this instance at contact 388 of the "tens" register 302 instead of at contact 130

48 of 203 as it was in the previous instances. Since registers 203, 300 and 301 are at normal, their contacts 26, 387 and 358 will be closed and switching device 240 instead of 5 coming to rest in positions 1, 2 and 4, will be moved on under the influence of its stepping magnet 299 through circuits already described until it arrives at position 6. In this position, since the "tens" register 302 10 is off normal, the circuit of 299 will be open at contact 386 and 240 will come to rest, while since contact 387 is closed and relay 309 energized the circuit of stepping magnet 390 of the "tens" register will be established 15 over the following path: battery, 390, 387, 368, 369, 357, 43, 41, 25, 352, 304, ground. As previously described, as soon as 302 reaches normal it opens its contact 387 and closes 386 thus transferring the stepping circuit 20 through interrupter 304 to stepping magnet 299. Switching device 240 thereupon is moved from position 6 through 7 to 8 energizing in succession relays 311 and 312 after which "units" register 303 is returned 25 to normal followed by a like return of switching device 240 as soon as contact 394 is closed.

In all these instances it will be remembered that as soon as the switching device 30 240 leaves normal, the circuit to ground through cut-off relay 206 is broken at contact 290, whereupon the trunk finder 202 is returned to normal. When the trunk finder 400 has been moved off normal it will be returned 35 when contact 399 of "units" register 303 is open upon the return of the latter to normal, or where the "units" register 303 has not been set up, upon the return to normal of "tens" register 302 and the opening 40 of its contact 374. Should the subscriber at 45 e¹ hang up his receiver immediately after removing it in preparation for a call, nevertheless he will have moved the trunk finder 202 off normal. But unless he held the receiver off the hook for a sufficient time for 50 the trunk finder 202 to connect with an idle trunk, it will return to normal under the influence of its stepping magnet 224, the circuit being as follows: battery 226, interrupter 225, 224, 227, 229, ground. If the receiver is not returned until after an idle trunk has been found, relay 291 will be energized and an alternate circuit to ground for the slow-release relay 283 closed over the 55 following path: battery, 283, 265, 266, conductor 236, 480, ground. Therefore, when register line relay 281 is deenergized by hanging up the receiver, its contact 297 closes the circuit of stepping magnet 245 of 60 the ten-thousands register 203 over the following path: battery 12, 245, 10, 284, 296, 297, ground. Register 203 is moved one step off normal and contact 265 is broken thus opening the circuit of the slow-release relay 65 283. Contact 48 is closed and a circuit es-

tablished for stepping magnet 299 of switching device 240 over the following path: battery 280, 299, 73, 48, 298, ground. Stepping magnet 299 moves 240 from normal to position 1 when register 203 is returned to 70 normal under the influence of its stepping magnet 247, exactly the same as it is in the case of a premature disconnect occurring after the register 203 had been set. After register 203 has been returned to normal, 75 switching device 240 also will be returned to normal under the influence of its stepping magnet 299 in the manner heretofore described. That is, as soon as contact 26 of register 203 is closed, the circuit of 299 will 80 be closed, relays 288, 307, 309, and 312 will be energized in succession since the contacts 387, 358, 386 and 394 of the other registers are all closed, and the circuit of stepping magnet 299 will remain closed through the 85 interrupter 304 until switching device 240 returns to normal.

We claim—

1. In an automatic switching system the combination with a main office, a satellite office, subscribers' lines extending to said offices, and trunk lines between said offices, of other trunk lines local to said satellite, automatic switches for controlling the connection between subscribers' lines, calling 90 devices for controlling said switches, means operating under the control of said calling devices adapted normally to select an inter-office trunk line, and means adapted upon the manipulation of a calling device in accordance with the number of a subscriber's line connected to the same satellite as the one to which the calling subscriber's line is connected to prevent the selection of an inter-office trunk and to extend the connection 95 instead through a local trunk line. 100

2. In an automatic switching system the combination with a main office, a satellite office, subscribers' lines extending to said offices, and a group of trunk lines between 110 said offices, of another group of trunk lines local to said satellite, automatic switches, calling devices therefor, an automatic trunk finder at said satellite, and automatic discriminating means actuated under the control of calling devices when operated in accordance with the numbers of subscribers wanted adapted to render said trunk finder operative with respect to said inter-office trunk lines or to said local trunk lines according as to whether the calling and called subscribers' lines are connected to different offices or to one and the same satellite. 115

3. In an automatic switching system the combination with a main office, a satellite office, subscribers' lines extending to said offices, and a group of trunk lines between 120 said offices, another group of trunk lines local to said satellite, of means for finding an idle trunk line in either group, sub- 125 130

scribers' calling devices associated with said satellite, means controlled by said calling devices for rendering said trunk finding means operative with respect to the inter-office trunk lines, and automatic means operating when the line of the subscriber wanted is connected with the same satellite as the one to which the subscriber calling is connected adapted to render said controlled means inoperative and to render said trunk finding means operative with respect to the group of local trunk lines.

4. In an automatic switching system the combination with a main office, a satellite office, a group of trunk lines between said offices, of other trunk lines local to said satellite, subscribers' lines connected to said offices, automatic switches, calling devices therefor at the substations of said lines, a register sender at the satellite adapted to be set under the control of said calling devices to indicate the number of a wanted subscriber's line and to control in turn the operation of said automatic switching apparatus to connect the calling subscriber's line therewith, means associated with said register sender adapted when a subscriber of the satellite is calling a subscriber of the main office for extending the connection through an inter-office trunk line, but adapted when the line of the subscriber wanted is connected to the same satellite as the one to which the line of the subscriber calling is connected, for extending the connection to a local trunk line.

5. In an automatic switching system the combination with a main office, a satellite office, and a group of trunk lines between said offices, of other trunk lines local to said satellite, subscribers' lines connected to said offices, automatic switches, calling devices therefor at the substations of said lines, a register sender at the satellite adapted to be set under the control of said calling devices to indicate the number of a wanted subscriber's line and to control in turn the operation of said automatic switching apparatus to connect the calling subscriber's line therewith, means associated with said register sender adapted when a subscriber of the satellite is calling a subscriber of the main office for extending the connection through an inter-office trunk line, but adapted when the subscriber wanted is connected to the same satellite as the one to which the subscriber calling is connected, for extending the connection to a local trunk line and means, made operative upon a premature disconnection by the calling subscriber for returning said register to normal.

6. In an automatic switching system the combination with automatic switches for interconnecting any two subscribers' lines, of a register sender adapted to be set under the control of a calling subscriber to indicate

the numbers of wanted subscribers and to control in turn the operation of said automatic switches, and a switching device, operating automatically upon a premature disconnection by the calling subscriber, to return to normal any portion of said register sender and associated apparatus that may be off normal.

7. In an automatic switching system the combination with a main office, a satellite office, subscribers' lines extending to said offices, and trunk lines between said offices, other trunk lines local to said satellite, automatic switches for controlling the connection between subscribers' lines, calling devices for controlling said switches, a finder switch, and automatic means operating under the control of the calling devices when manipulated in accordance with the number of the subscriber wanted for causing said finder switch to select an inter-office trunk line or a local trunk line according as to whether the calling and called subscribers' lines are connected to different offices or to the one and the same satellite and means, made operative upon a premature disconnection by the calling subscriber, adapted to automatically return to normal any portion of said automatic discriminating means that may at the time be off normal.

8. In a multi-office automatic switching system, the combination with several main offices interconnected by trunk lines, of satellite offices having groups of trunk lines connecting each satellite with a main office and another group of trunk lines local to each satellite, subscribers' lines extending to said offices, means for finding an idle trunk line in either group, subscribers' calling devices associated with each satellite, means controlled by said calling devices for rendering said trunk finding means operative with respect to the inter-office trunk lines, and automatic means operating when the line of the subscriber wanted is connected with the same satellite as the one to which the line of the subscriber calling is connected adapted to render said controlled means inoperative and to render said trunk finding means operative with respect to the group of local trunk lines.

9. In a multi-office automatic switching system, the combination with several main offices interconnected by trunk lines, of satellite offices each connected to a main office by a group of trunks and having another group of trunks local to the satellite, subscribers' lines connected to said offices, automatic switches, calling devices therefor at the substations of said lines, a register sender at the satellite adapted to be set under the control of said calling devices to indicate the numbers of wanted subscribers and to control in turn the operation of said automatic switching apparatus to connect

- the calling subscriber's line therewith, means associated with said register sender adapted when a subscriber of the satellite is calling a subscriber of the main office for extending 5 the connection through an inter-office trunk line, but adapted when the line of the subscriber wanted is connected to the same satellite as the one to which the line of the subscriber calling is connected, for extending 10 ing the connection to a local trunk line.
10. In an automatic switching system, the combination with a plurality of central stations and substation lines extending thereto, of interoffice and intraoffice trunks for connecting the substation lines, trunk selecting apparatus, calling apparatus upon which the numbers of the substation lines may be registered, automatic means operating in accordance with the digit groups registered 15 upon the calling apparatus to determine the selection of interoffice or intraoffice trunks, and means made operative upon a premature disconnection by the calling subscriber, adapted to automatically return to normal 20 any portion of said calling apparatus that 25 may at the time be off normal.

11. In an automatic switching system, the combination with a plurality of central stations and substation lines extending thereto, of interoffice and intraoffice trunks for 30 connecting the substation lines, selector switches, trunk selecting apparatus, apparatus upon which the numbers of a called substation may be registered and subsequently automatically transmitted to selector switches, automatic means operating in accordance with the digit groups registered 35 upon said apparatus to determine the selection of interoffice or intraoffice trunks, and means made operative on a premature disconnection by the calling subscriber adapted to return to normal any portion of the call registering apparatus that may have been set.

In witness whereof we, FRANK N. REEVES 45 and ALBEN E. LUNDELL, hereunto subscribe our names this 3rd day of July, A. D. 1912.

FRANK N. REEVES.
ALBEN E. LUNDELL.
